(57) **CLAIM**

The ornamental design for an egg tray for refrigerator as shown and described.

DESCRIPTION

1.1: Perspective

1.2: Right

1.3: Left

1.4: Front

1.5: Rear

1.6: Top

1.7: Bottom

1.8: Enlarged view of portion 1.8 in 1.1

1.9: Enlarged view of portion 1.9 in 1.1

The evenly dashed broken lines in the reproductions illustrate portions of the egg tray for refrigerator which form no part of the claimed design.

The unevenly dashed broken lines illustrate the boundary of the enlarged view and form no part of the claimed design.
